UNITED STATES PATENT OFFICE.

MORRIS A. HEIMANN, OF ST. LOUIS, MISSOURI.

DESIGN FOR A SKIRT-HANGER.

SPECIFICATION forming part of Design No. 32,764, dated May 29, 1900.

Application filed April 30, 1900. Serial No. 15,013. Term of patent 7 years.

To all whom it may concern:

Be it known that I, MORRIS A. HEIMANN, of the city of St. Louis, State of Missouri, have invented a new and original Design for a Skirt-Hanger, of which the following is a full, clear, and exact description, reference being had to the accompanying drawing, forming a part hereof.

The figure shows my complete design.

As shown, the essential or material feature of my design consists of a vertical handle 1, formed from a single wire bent double and twisted into spiral form and having a hook 2 formed on its upper end. At 3 the spiral handle ends and the two ends of the single wire forming said handle are bent outwardly and upwardly, forming arms 4. The said arms are bent at 5, forming eyes 6, and the outer ends of the said arms are bent downwardly and outwardly at suitable angles from 20 the arms 4, forming hooks 7.

I claim—

The design for a skirt-hanger, substantially as herein shown and described.

In testimony whereof I affix my signature 25 in presence of two witnesses.

MORRIS A. HEIMANN.
